HOWARD A. MORRIS, OF TOLEDO, OHIO, ASSIGNOR TO THE AUTOMAT MOLDING & FOLDING COMPANY, OF TOLEDO, OHIO, A CORPORATION OF OHIO

ARTICLE STACKING MECHANISM

Application filed October 23, 1929. Serial No. 401,892.

This invention relates to packing machines, but more particularly to machines to wrap and package articles such as butter, oleomargarine, or other similar plastic materials.

An object of this invention is to provide a simple and efficient article wrapping and packaging machine, which is adjustable for handling articles of different sizes so that 10 a single machine may be employed to wrap one or a plurality of articles, arrange them suitably for packaging, and subsequently enclose them in a carton.

Another object is to provide a simple and 15 efficient mechanism for arranging articles in a stack preparatory to packaging, such mechanism being operable to handle articles of different sizes, or may be rendered inoperative so that the machine may function with- 20 out the operation of the stacking device.

A further object is to provide an article 25 wrapping and packaging machine having the new and improved features of construction, arrangement and operation hereinafter described.

The invention is shown by way of illustration in the accompanying drawings, in which:

Fig. 1 is a side elevation of an article 30 wrapping and packaging machine;

Fig. 2 is a top plan view of a portion of a machine showing the article wrapping mechanism, and the stacking housing and associated parts;

Fig. 3 is a side elevation of the mechanism 35 shown in Fig. 2 more clearly showing the article stacking mechanism;

Fig. 4 is a transverse sectional elevation 40 on the line 4-4 of Fig. 2 showing the elevator in its raised position;

Figs. 5 and 6 are diagrammatic views 45 showing the operation of the stacker or elevator for use in handling one-quarter pound bars;

Figs. 7 and 8 are diagrammatic views of the stacking mechanism handling one-half pound bars;

Fig. 9 is a diagrammatic view of the mech- 50 anism adjusted for handling one pound bars,

in which the elevator is rendered inoperative; and

Fig. 10 is a perspective view of the mechanism for folding the end and side flaps about the article.

The illustrated embodiment of the invention comprises a machine for wrapping and packaging bars of butter, oleomargarine, and the like, in which the bars are first delivered to feeding mechanism A, which advances the 60 articles step by step along a table, and from which a ram B advances individual articles along a guide C. Sheets of relatively flexible material, such as parchment paper, are delivered into the path of movement of the 65 bars by a sheet feeding and severing mechanism D. The bars are then further advanced by the ram B through mechanism E, which partially folds the sheets about the individual articles. The folding of the sheets about 70 the articles is completed by mechanism F shown in detail in Fig. 10.

The articles are then arranged in suitable 75 manner for packaging, having been previously completely wrapped with the sheet ma- 80 terial. In a case of one-quarter pound bars, the bars are arranged in a symmetrical stack containing four, whereas, in the case of one- 85 half pound bars, two bars are stacked one upon the other, but the one-pound bars are advanced without further arrangement, the 90 stacking mechanism being adjusted to inoperative position. Carton blanks are then delivered to the path of movement of the articles by carton feeding mechanism G, and during the further advance of the unit carton 95 folding mechanism H is provided for packaging the unit.

Detail description of all the above men- 100 tioned parts is considered unnecessary, be- 90 cause this invention is particularly concerned with the stacking mechanism and associated parts. While there are differences in the driving and control mechanism, this machine closely resembles that shown in the United States patent to John P. Aldrich et al., No. 1,573,024, of February 16th, 1926. It is be- 95 lieved that the above brief description of the complete apparatus is sufficient to enable those skilled in the art clearly to understand 100

the following description concerning the article stacking mechanism.

Articles are advanced step by step in the forward or advanced portion of the machine by a feed frame 10, to which is imparted horizontal reciprocatory movements as well as vertical movements at the beginning and end portion of the stroke, the path of movement of the frame 10 being indicated by the dotted lines 10^a. The mechanism for operating is clearly shown and described in the above mentioned patent, it being deemed sufficient to point out that reciprocatory movements are imparted by an arm 11, and vertical movements are imparted thereto by a lever and link arrangement 12.

Mounted on the rear end of the feed frame 10 is a paddle 13, and spaced forwardly of the paddle 13 is another paddle 14, these paddles being adapted to engage articles on the guide C and advance them progressively toward the discharge end of the machine. Pivoted to the frame 10 in the region of the paddle 13 is an elevator 15, comprising laterally disposed tongues, which are fixed at one end to a shaft 16, rotatable in a bearing 17 on the frame 10.

Normally, the tongues comprising the elevator 15 are held by gravity in downward position away from the guide C. A dog 18, associated with the elevator 15, is engageable with a roller 19 mounted on the side frame of the machine, and is adapted to lift the elevator so that the upper surface of the tongues are disposed in a substantially horizontal position suitable to engage the underside of the bars and raise them, as will hereinafter be described. The dog 18 is integral with a collar 20 and an arm 21, also integral with the collar 20, extends outwardly therefrom slightly at an angle to the dog 18. Secured to the elevator 15 is an arm 22, the end of which terminates adjacent the end portion of the arm 21. Interposed between the arms 21 and 22 is a coiled spring 23, the arrangement being such that when the dog 18 abuts against the roller 19 causing the elevator to swing in a clockwise direction, the force is imparted through the spring 23, thereby to compensate for any derangement of parts, and to provide a yieldable engagement between the bars and elevator.

By inspection of the diagram 10^a indicating the path of travel of the pusher frame 10, the operation of the elevator 15 will be apparent. As the feed frame is retracting in its lowered position the dog 18 encounters the roller 19, causing the elevator to assume a substantially horizontal position. Thereafter, the elevator is positioned directly beneath the guideway C to engage one or more articles. Thereafter, as the frame 10 moves upwardly the elevator 15 engages an article or articles on the guide C, and elevates

them to the upper portion of the stacking housing 24.

As above pointed out, the ram B advances individual articles along the guide C, and the operation of this ram is such as to deliver individual articles through a portion of the sheet wrapping mechanism E to a point slightly in rear of the stacking housing 24. In this position the sheet is partially wrapped about the articles leaving end flaps and side flaps projecting therefrom (see Fig. 10). These flaps are folded in the following manner. First, L-shaped levers 25 disposed on opposite sides of the guide C move inwardly toward each other to fold the end flaps toward each other. Thereafter, levers 26 also positioned on opposite sides of the guide C move upwardly to fold the lower side flap, and the upper side flap is thereafter folded over against the lower folded side flap by a folding plate 27 disposed above the path of movement of the articles. It will thus be seen that the articles are wrapped in sheet material before reaching the stacking housing 24.

The ram B operated to form a row of articles of a divisible number; in the case of one-quarter pound bars, a row of four bars is formed; in the case of one-half pound bars, a row of two bars is formed, and when one pound bars are being handled the elevator 15 is rendered inoperative, it being desired in this instance to provide a package containing one pound of butter, oleomargarine, or the like, containing either four one-quarter pound bars, two one-half pound bars, or a one pound bar, as desired. In order to render the stacking mechanism inoperative, the arms 18 and 21 are moved as a unit in a counter clockwise direction away from the arm 22, thereby to allow the elevator to hang downwardly out of operative position (Fig. 9).

As the elevator 15 moves upwardly it carries with it either two one-quarter pound bars, or one one-half pound bar, as the case may be. As shown in Fig. 4 side plates 28 are disposed on opposite sides of the guide C in position to engage the ends of the bars, adjustable coil springs 29 urging the plates into engagement with the bars. The spring pressure is sufficiently yieldable to permit the elevator 15 to carry the bars upwardly. Each side plate 28 is provided at its upper edge with an inwardly projecting ledge 30 so that as the bars are moved upwardly the plates 28 are cammed inwardly to permit the bars to pass thereover, and after the bars have passed the ledge 30 the springs 29 return the plates 28 to normal position so that the ledges 30 provide a support for the elevated bars. Pressure plates 31 disposed above the plates 28 engage the ends of the bars in elevated position, adjustable springs 32 providing a yielding pressure to hold the

plates 31 against the bars and retain the latter in the desired position. As shown, the lower edges of the plates 31 are beveled at 33 so that the plates 31 do not interfere with the 5 upward movement of the bars.

In order to prevent unfolding of the parchment paper which encloses the rear articles of the elevated pair in the case of one-quarter pound bars, or the rear side of the 10 sheet enclosing the elevated half-pound bar, stop plates 34 are so arranged that one side of the article abuts thereagainst.

Forming a yieldable stop for the movement of the articles to position them properly for stacking, fingers 35 are fixed to a transverse rod 36 disposed above the stacking housing, and a coil spring 37 normally holds the fingers in a substantially vertical position. These fingers also assist in holding 20 the articles against the abutment plates 34 to prevent unwrapping thereof.

From the above description it will be apparent that after a predetermined number of wrapped bars have been elevated in the 25 stacking housing the feed frame 10 commences its advancing movement, and at that time the rear paddle 13 engages the rear articles remaining in the row previously formed. Thereafter, as the frame advances 30 the rear articles are advanced along the guide C to a position beneath the elevated article or articles, and continued movement serves to advance the stack so formed as a unit along the guide C, the forward paddle 14 having advanced the stack previously formed 35 into engagement with a carton W (Fig. 6), and succeeding paddles (not shown) carried by the frame 10 serve to complete the movement of the stacks along the guide C and 40 through the carton folding mechanism H above referred to, and clearly described in the above mentioned patent. It will be obvious that the above stacking mechanism may be used to stack articles of different sizes, it 45 being understood that the operation of the ram B is varied according to the size of the article being handled. For example, in handling one-quarter pound bars it will operate more rapidly in order to provide a row 50 of four wrapped articles, whereas in the case of one-half pound bars the row contains but two bars.

It is not considered necessary to explain 55 in detail the operating mechanism for controlling the rate of operation of the various parts. Suffice it to say that a transmission T is provided for changing the speed of operation of the various parts so that the parts may operate more rapidly or more slowly, 60 according to the size of the articles being handled.

It is to be understood that the above description is given by way of illustration and 65 not of limitation, and numerous changes in details of construction, arrangement and op-

eration may be effected without departing from the spirit of the invention.

What I claim as new and desire to secure by Letters Patent is:

1. In a machine for packing articles of substantially the same size, means to form a row of articles, means to elevate a predetermined number of the foremost articles in the row a distance substantially equal to the thickness thereof, and means to impart relative movement between the remaining articles and those elevated to form a stack. 70

2. In a machine for packing articles, means to form a row of articles, means to elevate a predetermined number of the foremost articles in said row a distance substantially equal to the thickness thereof, and means to advance the rear articles to form a stack 80 with the elevated articles.

3. In a machine for packing articles, means to form a row of divisible number of articles, means to elevate the foremost half of said number a distance substantially equal to the thickness thereof, and means to impart relative movement between the remaining 90 articles and elevated articles to form a stack. 85

4. In a machine for packing articles, means to form a row of articles, means to elevate a predetermined number of articles in the row a distance substantially equal to the thickness thereof, means independent of said elevating means for holding said articles in elevated position, and means to impart relative movement between the remaining 100 articles and those elevated to form a stack. 95

5. In a machine for packing articles, means to form a row of articles, an elevator for elevating a number of the foremost articles in the row a distance substantially equal to the thickness thereof, means independent of said elevator for yieldingly holding said articles in elevated position, and means to advance the rear articles of the row to form a 105 stack with the elevated articles. 110

6. In a machine for packing articles, means to form a row of articles containing a divisible number, an elevator for elevating the foremost half of the row a distance substantially equal to the thickness thereof, yieldable means for holding said articles in elevated position, and means for advancing the remaining articles to position beneath the elevated articles to form a stack. 115

7. In a machine for packing articles, means to form a row of articles, an elevator for lifting a predetermined number of articles from the row a distance substantially equal to the thickness thereof, spring means for holding said articles in elevated position, and means for advancing the remaining articles of the row beneath said elevated articles and thereafter advancing the stack of articles so formed. 120

8. In a machine for packing articles, a 125

guide, means for advancing articles step by step along said guide to form a row containing a divisible number of articles, a yieldable stop against which the foremost article of said row abuts, an elevator for elevating one-half the number of articles in said row, yieldable means for retaining said articles in elevated position, and means for advancing the remaining articles in said row to a position beneath the elevated articles, thereby to perform a symmetrical stack.

9. In a machine for packing articles, means to form a row of articles individually wrapped in flexible sheet material, an elevator for elevating a predetermined number of articles of said row with relation to the remaining articles, yieldable means engaging the ends of said articles to hold them in elevated position and prevent unwrapping thereof, means engaging one side of the row of said elevated articles to prevent unwrapping of the wrapping sheet, and a paddle movable with said elevator for advancing the remaining articles of the row to a position beneath said elevated articles to form a stack.

10. In a machine for packing articles, means to form a row of articles individually wrapped in flexible sheet material, an elevator for elevating a predetermined number of articles of said row with relation to the remaining articles, yieldable means engaging the ends of said articles to hold them in elevated position and prevent unwrapping thereof, means engaging one side of the row of said elevated articles to prevent unwrapping of the wrapping sheet, and a paddle movable with said elevator for advancing the remaining articles of the row to a position beneath said elevated articles to form a stack.

11. In a machine for packing articles, means to provide a row of articles with the opposite ends in alignment, said means being operable to move said articles individually into alignment, means movable vertically in a direction at right angles to the direction of movement of said articles for moving a predetermined number of the foremost articles in the row a distance substantially equal to the thickness of said articles, and means to impart relative movement between the remaining articles of the row and those previously moved to arrange same in stacked formation.

In testimony whereof I have hereunto signed my name to this specification.

HOWARD A. MORRIS.
